UNITED STATES PATENT OFFICE.

HIRAM STEVENS MAXIM, OF LONDON, ENGLAND.

PROJECTILE.

SPECIFICATION forming part of Letters Patent No. 443,101, dated December 23, 1890.

Application filed April 11, 1890. Serial No. 347,495. (No model.)

To all whom it may concern:

Be it known that I, HIRAM STEVENS MAXIM, mechanical engineer, a citizen of the United States, and a resident of London, England, 5 have invented certain new and useful Improvements relating to Armor-Piercing and other Projectiles or Shells, of which the following is a specification, reference being had to the accompanying drawings.

10 My invention relates to armor-piercing and other projectiles or shells, and is designed to afford the means for preventing or diminishing the rapid and destructive wear or erosion which takes place in guns wherein heavy 15 charges of powder are employed with projectiles or shells as heretofore constructed. This destructive action or erosion usually occurs in the bore of the gun at or near the commencement of the rifling thereof, and is due 20 to the escape or rush of the gases between the projectile and the barrel. It has been found that some of the most powerful guns heretofore constructed for armor-piercing are by such erosion rendered practically unserv- 25 iceable after they have been used for firing, say, one hundred rounds, and that in some cases they are destroyed with much greater rapidity. By reason of this rapid wear and the enormous cost of manufacture of such 30 guns the firing of each individual shot involves a very large expenditure of money, the expenditure represented by the loss due to wear and tear of the gun being additional to and greatly exceeding that represented by 35 the loss of the powder-charge and of the projectile when the latter is not recovered.

With a view to prevent the erosion of guns in the manner above mentioned, projectiles have heretofore been provided with a ring of 40 copper or other suitable metal, designed, in some instances, to be expanded and intended to fit into the grooves of the rifling and to serve as a gas-check, and also as a driving-ring, which by its engagement with the 45 rifling will insure rotation of the projectile about its axis. When, however, by the explosion of the powder-charge in the chamber of a gun a pressure of, say, twenty tons per 50 square inch is set up in the said chamber, the tendency of the gas to escape between the projectile and the barrel is very great,

and the copper or other rings heretofore employed have not proved effective in the case of such high pressures—that is to say, although the said ring may serve its purpose 55 as a driving-ring it does not act efficiently as a gas-check, chiefly for the following reason, viz: As very rapid rotation has to be imparted to the projectile in the short space of time which it takes to travel along the bore 60 of the gun, the driving-ring on entering the rifling is subjected to very great torsional and shearing stresses. Consequently the projections formed on the said ring are compressed and abraded by the driving side of 65 the grooves of the rifling to such an extent that the said ring does not fit the said grooves with sufficient accuracy to completely close the space between the projectile and the interior surface or bore of the gun, small pas- 70 sages being left between the other side of the grooves and the projections formed on the driving-ring. The rush of gas through the passages thus left rapidly erodes the steel of which the gun or the liner thereof is composed, and shortens to a very great extent 75 the life of the gun, the steel being eaten away almost as rapidly as ice would be destroyed by a stream of boiling water.

Now the object of my invention is to provide for effectually preventing the escape or rush of gas between the projectile or shell and the barrel, so that there will be but slight erosion of the steel tube or liner and the life of the gun will be greatly prolonged. To accomplish this result I provide for the complete obturation of the bore of the gun by means of a gas-check of soft or ductile metal or other yielding or plastic material, which is suitably arranged upon the projectile or shell 80 in addition to the ordinary driving-ring of copper, or similar metal, which by its engagement with the rifling effects the rotation of the projectile. I arrange the said gas-check between the body of the projectile and a part 85 which is movable relatively thereto in such a manner that when the said projectile is fired from a gun the gas-check will be subjected to pressure, and thus forced outward against the interior surface or bore of the gun. The em- 90 ployment of this gas-check in combination with an ordinary driving-ring is an important 95 100

feature of my said invention, as no metal which has sufficient strength to resist the torsional and shearing stresses to which the driving-ring is subjected by the rifling of the 5 gun would be sufficiently ductile or plastic to be forced outward in such a manner as to fill up all the cavities or spaces between the projectile and the barrel.

I find it advantageous to so construct my 10 improved projectile that the front and rear portions thereof are movable longitudinally and capable of rotation relatively to each other and have between them one or more air chambers or spaces, and to arrange be- 15 tween the said two parts of the projectile a gas-check composed of one or more rings or annular pieces of soft or ductile metal or other suitable packing surrounding the said chamber or chambers, so that the surface of 20 the rear portion of the projectile which bears against the said packing will be of less area than the surface thereof acted upon by the pressure in the chamber of the gun, and conse- 25 quently in the firing of the projectile from a gun the pressure per square inch exerted upon the said packing will be correspondingly greater than that of the gases in rear of the projectile, as hereinafter more fully explained.

When I make my projectile with two por- 30 tions capable of rotation relatively to each other as above described, I sometimes provide the rear portion of the said projectile with a ring of copper or similar metal, which serves as a driving-ring to effect the rotation 35 of the said rear portion of the projectile, and also acts efficiently as a gas-check.

In the accompanying drawings I have shown how my said invention may be conveniently and advantageously carried into practice.

40 Figure 1 is a longitudinal central section, and Figs. 2 and 3 are side elevations, partly in longitudinal central section, showing different forms of projectiles or shells constructed according to my said invention.

45 a is a portion of a rifled gun.

A is the main portion or body of the said projectile or shell.

B is a cap or base secured to the rear end thereof, as hereinafter described.

50 C is a plug or block fixed in the rear end of the body A.

D is a screw-bolt for securing the cap or base B to the main portion or body A, while permitting it to move longitudinally and to 55 rotate relatively thereto.

E is a driving-ring of copper or similar metal, such as those ordinarily used on projectiles or shells for large guns.

60 E' is the ordinary steady-ring.

F is a ring of copper or similar metal, which is secured to the movable cap or base B for the purposes hereinafter mentioned.

In the projectile shown in Fig. 1 the plug or block C is formed with an annular projec- 65 tion C', which fits into a corresponding recess or cavity B' in the cap or base B in such a manner that the said cap or base can move a

short distance forward upon the said projec- 70 tion. Two annular air-chambers G are thus formed between the two parts A B of the projectile. The said rear portion or base B is designed to be moved forward relatively to the body A when acted upon by the pressure of the gases generated by the explosion of the powder-charge in the gun, for the purpose 75 hereinafter explained.

H H' are two rings or annular pieces of lead or other soft or ductile metal, or of stiff fibrous packing or similar material, which are arranged between and bear against the adjacent surfaces of the said two parts A B of the projectile. Between these rings H H' is arranged another ring or layer J', of softer or more easily compressible or more plastic packing, consisting, for instance, of a mixture of 80 asbestos, plumbago, Burgundy pitch, Russian tallow, and beeswax. This easily-compressible or plastic packing will at the commencement of the forward movement of the rear portion of the projectile relatively to the body 85 thereof be forced outward against the interior surface or bore of the gun, and as the pressure to which the said rear portion of the projectile is subjected increases the rings of stiffer or harder packing will also be forced 90 outward and will prevent escape of the softer packing between the projectile and the bore of the gun. These three rings of packing 95 form the gas-check or obturator. It is obvious, however, that I can employ any other 100 convenient number of rings of the same or other suitable material, if desired. The forward ring or annular piece H of soft metal or stiff fibrous packing may, if desired, be made slightly cup-shaped or formed with a thickened rim or flange extending a short distance 105 forward, as shown.

The screw-bolt D for securing together the two parts A B of the projectile with the packing or gas-check between them is passed 110 through the movable rear portion or base B and screwed into the plug or block C in the forward portion or body A of the projectile, a gas-tight joint being made between the said bolt and the cap or base B by means of 115 suitable packing, so that the said cap or base is free to slide upon the said bolt, while the entrance of gas to the air-chamber G is avoided. For forming the said gas-tight joint I sometimes provide in the rear portion or 120 base B an annular taper or conical chamber or recess B², in which I place soft metal or other suitable packing K. In combination with this packing I provide a disk or annular piece L, of soft metal or other suitable material, which is inserted in a dovetail recess or cavity in the rear portion or base B, or is otherwise secured thereto. When the said rear portion B is moved forward upon the bolt D, the pressure of the gases, acting upon 125 the said disk L, will force the said disk and the packing into the said conical recess B², and the packing will thus be tightly wedged against the said bolt, and will prevent the 130

entrance of the gases into the chambers or spaces G. The said screw-bolt D can be used, if desired, for imparting an initial compression to the packing between the two parts of the projectile before the said projectile is inserted in the gun. The said bolt, moreover, affords the following advantage, viz: In target practice or in testing the gun or the gun mounting, when there is no necessity for great rapidity of firing, the projectile may be rammed into place in the gun-barrel with sufficient force to prevent its turning too freely in the barrel, and then the bolt D can be screwed up with a long spanner or in any other convenient manner, thus squeezing the packing or gas-check outward against the interior surface or bore of the gun. This operation very effectually prevents any slight erosion that might take place by the gases escaping between the projectile and the barrel before the inertia of the cap or base B has been overcome, and the gas-check forced outward by the pressure of the gases generated by the explosion.

It is obvious that I can, if desired, employ other means for securing together the two parts of the projectile with the gas-check between them, and for compressing the said gas-check by hand, for the purpose above specified.

In the case of an explosive projectile or shell it is advantageous to arrange the fuse in a chamber or cavity D' in the forward end of the bolt D, and to secure it therein by means of a screw-threaded ring or plug M, or in any other convenient manner. I thus provide for the removal and replacement of the fuse with the said bolt without disturbing other parts of the projectile and without detaching the parts of the fuse from each other. When the explosion occurs and the pressure is developed in the chamber of the gun, this pressure, acting upon the movable cap or base B, drives the same forward relatively to the main portion or body A, and the packing or gas-check is subjected to pressure between these parts, so that first the more easily compressible packing and then the harder or stiffer packing are squeezed outward into the space or cavity around the projectile between the driving-rings E F. A gas-tight joint is thus made between the projectile and the barrel before the inertia of the main portion or body of the projectile is overcome and before the driving-ring E enters the rifling.

It will be readily seen that the area of the annular surface of the cap or base B, which acts upon the packing or gas-check, is less than that of its rear surface, which is acted upon by the pressure generated by the explosion of the powder-charge in the gun. Therefore the pressure per square inch exerted upon the said packing or gas-check will at all times during the entire movement of the projectile through the bore of the gun be greater than that in rear of the projectile—that is to say, from the moment when the ini-

tial pressure is set up by the explosion until the projectile has left the muzzle of the gun the passage of the gas between the projectile and the bore of the gun is opposed by soft or ductile metal or other compressible or plastic material, which is under a higher pressure per square inch than that of the gas, the pressure from the chamber being opposed by a greater pressure. In other words, the pressure to which the packing between the two driving-rings is subjected not only insures the formation of a gas-tight joint before the said driving-rings have entered the rifling, but during the entire passage of the projectile through the rifling of the gun the packing is pressed outward into the grooves of the rifling, filling every little scratch and hole, and thus effectually preventing escape of the gases, and consequent erosion of the bore of the gun. The packing is, moreover, confined or imprisoned between the two driving-rings, and therefore cannot be displaced.

I prefer to so construct and arrange the parts that the packing forced or squeezed out from between the forward and rear portions of the projectile will fill the recess or cavity around the projectile between the two driving-rings E F.

It will be seen that the driving-ring F has but little work to do in bringing about by its engagement with the rifling the rotation of the part B, to which it is attached. The said driving-ring F will therefore be but slightly damaged or abraded by the torsional or shearing stresses, the said part B being free to revolve on the body A of the projectile. Consequently the driving-ring F will act much more efficiently as a gas-check than the driving-ring E, and will assist in effecting a complete obturation of the bore of the gun for the purpose above specified.

The ring or rings of packing forming the gas-check or obturator may be of various materials—for instance, lead, canvas and gum, asbestos, plumbago and tallow, jute or hemp mixed with composition such as that used for the manufacture of printers' rollers. In fact, any suitable material or composition or combination of materials may be used, which when subjected to pressure, as above described, will be forced outward, so as to fit gas-tight into the rifling of the gun.

I prefer to use some soft or plastic material to form the central ring or layer J of the packing, so that a comparatively small pressure will suffice to force it outward. The rings or layers H H' may be made of sheet-lead or of lead pulverized and mixed with wax to render it more difficult to force through a small opening; or they may be made of strong fibrous material, which cannot be forced through a small opening by the pressure of the gases.

It is obvious that instead of employing parallel surfaces, between which the packing is arranged, I can, if desired, make the said surfaces conical, so that the distance between them increases from their inner to their outer

edges, as shown, for example, in Fig. 2. Moreover, the packing may, if desired, fill the space between the driving-rings E F before it is compressed, as also shown in this figure.

5. I sometimes dispense with the rear driving-ring, as shown in Fig. 3.

It will be seen that in my improved projectile there is a driving-ring of comparatively hard metal, such as copper, and in rear of this driving-ring is arranged between the two parts of the projectile the gas-check or obturator of softer or more ductile metal, such as lead, or of yielding or plastic material, such as those above mentioned. In the firing of 15 the projectile from the gun the said driving-ring enters the rifling and insures the rotation of the main portion or body of the projectile. The gas-check is expanded by the pressure of the gases acting upon the rear 20 part of the projectile and enters the rifling in rear of the said driving-ring, thus preventing any escape of gas between the projectile and the barrel.

The location of the gas check or obturator 25 at the base, rather than at any other convenient part of the projectile, is not imperative.

Having now particularly described and ascertained the nature of my said invention and in what manner the same is to be performed, 30 I wish it understood that I do not claim, generally or irrespectively of my improvements herein described, the employment of a ring of soft or ductile metal arranged between the body of the projectile and a rear portion or 35 base movable relatively thereto, as I am aware that such a ring has been used on a projectile to serve both as a driving-ring and as a gas-check; but in order to insure the requisite rotation of the projectile and at the same time 40 effectually prevent any escape of gas between the projectile and the barrel it is necessary to employ rings of different kinds of material on the said projectile, as above described, one 45 ring of hard material to perform the work of rotating the projectile and another ring of material sufficiently ductile or plastic to be forced into and to accurately fill the rifling when subjected to the pressure of the gases, 50 in the manner above set forth.

50. What I claim is—

1. A projectile having a driving-ring of copper or other metal sufficiently hard to engage with the rifling and cause the rotation of the projectile about its axis, and a gas-check or obturator of metal or material softer or more ductile than that of the driving-ring, for the purpose above specified.

2. A projectile having a driving-ring for insuring by its engagement with the rifling 60 of a gun the rotation of the said projectile about its axis, and a separate gas-check or obturator of soft or ductile metal or other plastic or yielding packing adapted to be forced outward against the interior surface or bore 65 of the gun by the pressure of the gases in rear of the projectile.

3. The combination, with the body of a pro-

jectile having a driving-ring thereon, of a longitudinally-movable cap or base attached thereto, and a gas-check or obturator arranged 70 between the said body and the movable cap or base, for the purposes above specified.

4. The combination, with the body of a projectile having a driving-ring thereon, of packing arranged at the rear of the said body, and a longitudinally-movable cap or base attached to the said body and having an annular surface which bears against the said packing, whereby in the firing of the projectile from a gun the said packing will be subjected to a 80 pressure per square inch greater than that in rear of the projectile, for the purpose above specified.

5. The combination, with the body of a projectile having a driving-ring thereon, of a longitudinally-movable cap or base, a gas-check or obturator arranged between the said body and the movable cap or base, and a screw-bolt whereby the said cap or base is secured to the body of the projectile, and whereby the 90 said gas-check or obturator may be compressed, substantially as and for the purposes set forth.

6. The combination, with the body of a projectile having a driving-ring thereon, of a cap 95 or base attached to the said body so that it is capable of rotation relatively thereto, and a driving-ring secured upon the said cap or base, substantially as and for the purposes set forth.

7. The combination, with the body of a projectile or shell having a driving-ring thereon, of a longitudinally-movable and rotatable cap or base attached thereto, a driving-ring secured upon the said cap or base, and a gas-check or obturator arranged between the said 105 cap or base and the body of the projectile, substantially as and for the purposes set forth.

8. The combination, with the body of a projectile having a driving-ring thereon, of a movable cap or base, a screw-bolt for securing the said cap or base to the body of the projectile and having a chamber for the fuse, and a gas-check or obturator arranged between the said cap or base and the body of the projectile, substantially as and for the purposes set forth.

9. The combination, with the body of a projectile having a driving-ring thereon, of a 120 movable cap or base also provided with a driving-ring, a screw-bolt for securing the said cap or base to the body of the projectile, and a gas-check or obturator arranged between the said body and the movable cap or base, 125 substantially as and for the purposes set forth.

10. The combination, with the body of a projectile, of a movable cap or base, a gas-check or obturator arranged between the said 130 body and the movable cap or base, a screw-bolt for securing the said cap or base to the body of the projectile, packing contained in a taper or conical recess or cavity in the said

cap or base and surrounding the said screw-bolt, and a disk or annular piece secured to said cap or base in rear of the said packing, substantially as and for the purposes set forth.

11. The combination, with the body of a projectile having a driving-ring thereon, of a movable cap or base attached thereto, and a gas-check or obturator arranged between the said body and the movable cap or base, and consisting of rings or annular pieces, one of which is formed of soft or easily-compressible or plastic material and others of harder or stiffer material, substantially as and for the purposes set forth.

12. A projectile or shell having a longitudinally-movable base or cap and provided with a driving-ring of copper or other metal sufficiently hard to insure the rotation of the projectile about its axis when fired from a gun, and with a gas-check or obturator of metal or other material which is softer or more ductile or plastic than that of the driving-ring, arranged in rear of the said driving-ring between the body of the projectile and the said movable base or cap, and a screw-bolt whereby the said base or cap is secured to the body of the projectile, and which can be screwed up by hand to compress the said gas-check, one or more chambers containing air or other easily-compressible substance being provided between the said body and the movable base or cap, for the purposes above specified.

the said body and the movable base or cap, for the purposes above specified.

13. A projectile or shell having a longitudinally-movable base or cap, and provided with a driving-ring of copper or other metal sufficiently hard to insure the rotation of the projectile about its axis when fired from a gun, and with a gas-check or obturator of metal or other material which is softer or more ductile or plastic than that of the driving-ring, arranged in rear of the said driving-ring between the body of the projectile and the said movable base or cap, and a screw-bolt whereby the said base or cap is secured to the body of the projectile, and which can be screwed up by hand to compress the said gas-check, one or more chambers containing air or other easily-compressible substance being provided between the said body and the movable base or cap, for the purposes above specified.

In testimony whereof I have hereunto signed my name in the presence of two subscribing witnesses.

HIRAM STEVENS MAXIM.
